UNITED STATES PATENT OFFICE.

WILLIAM LICHTENFELS, OF NEWARK, NEW JERSEY, ASSIGNOR TO NEW JERSEY CHAIN CORPORATION, OF NEWARK, NEW JERSEY, A CORPORATION OF NEW JERSEY.

BRACELET.

Application filed July 12, 1926. Serial No. 121,808.

This invention relates to an improvement in the construction of chains or bracelets formed of a plurality of connected extendible links; and the object of this invention is the construction of such a chain or bracelet which comprises a series of box links connected by frame links, each frame link being mounted to slide within its box link and a spring being provided in each box link acting upon it and the frame link to press both toward contracted position.

A further object of the invention is the provision of such an extendible bracelet in which the box links each have a resilient wall to which one end of a frame-shaped connecting link in the next adjacent box link is detachably connected.

With these and other objects in view, the invention consists of certain novel features of construction, as will be more fully described, and particularly pointed out in the appended claims.

In the accompanying drawings:

Figure 1 is a perspective view showing a plurality of box links as connected by frame-shaped links which are open on their top and bottom sides.

Figure 2 shows a blank as cut from sheet stock and which when folded forms the box link.

Figure 3 shows this blank as partially folded.

Figure 4 is a box link completely folded from the blank.

Figure 5 is a transverse section through the box link.

Figure 6 is a longitudinal section through the box link.

Figure 7 is a perspective view of the frame link.

Figure 8 is a plan view in section showing the frame link as having its body portion partially housed and guided to slide endways in a box link.

Figure 9 is a central sectional elevation showing the box link as having a resilient end wall with the lip folded under the bottom wall thereof.

Figure 10 is a slight modification in which the bottom wall is formed resilient and adapted to be depressed between the side walls of the box link to move readily to permit detachment of the frame link therefrom.

It is found in the practical construction and operation of extendible bracelets or chains of this character, of advantage in some instances, to form the links very thin, whereby they will lie flat and close to the arm of the wearer; also to form the bracelet with the minimum number of parts and one in which the links may be connected to and disconnected from each other for the purpose of inserting or removing a link to regulate the working length of the bracelet; and to reduce the expense of manufacture of the bracelet to the minimum; and the following is a detailed description of the present embodiment of my invention and showing one construction of bracelet by which these advantageous results may be obtained:—

With reference to the drawings 10 designates the box link member of my improved construction of expandible bracelet which is formed of sheet stock, as illustrated in Figure 4 and folded from a blank 11, one form of which is illustrated in Figure 2. This blank may be partially folded into the position illustrated in Figure 3 before being completely closed into finished position to permit the connecting frame link or yoke link 12 to be inserted thereinto.

This box link is provided with a top wall 13, bottom wall 14, opposite side walls 15, one connecting end wall 16 and one resilient end wall 17 having a lip portion 18 folded over the back wall 14, the two end walls being slightly narrower than the body of the box leaving all four corners open as at 19, which permits the side arms 20 of the frame link housed therein to extend out therethrough to detachably engage the resilient end wall 17 of the next adjacent box link.

This frame link or yoke link may be formed of wire bent into shape or it may be blanked from sheet stock without a joint, if desired and open both top and bottom.

The links are detached one from the other by swinging the two adjacent box links at an angle to each other and springing outwardly or lifting up the end wall and its lip 18 slightly to permit the end bar 21 of the frame link to be passed thereover.

At the time this frame link or yoke is positioned in the box link and before the latter is entirely closed, a coiled spring 22 is also positioned in this box link to act between the end bar 23 of the frame link and

the end wall 16 of the box link serving to press the frame link towards housed or contracted position in its box link and at the same time permit the maximum amount of expansion between the links of the bracelet so that it may be flexibly extended sufficiently to be passed over the hand of the wearer when desired.

In some instances, instead of forming the bottom wall 14 of a width to lie upon the edges of the side walls 15, as illustrated in Figure 5, I may form the bottom wall 24, as illustrated in the modification in Figure 10, narrower to fit between the side walls 25 permitting it to be depressed slightly and cooperate with the resilient end wall 17 to permit the frame link or yoke to be more readily detached from its box link by springing this end wall 17 with its lip 18 outwardly and also this rear wall 24 slightly inwardly.

My improved bracelet is extremely simple and practical in construction, is effective in its operation, presents a broad surface to be ornamented when desired, may be made very thin to lie close against the wrist of the wearer, may be manufactured at the minimum cost, and is very handsome and attractive in appearance.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. An expandible bracelet comprising a series of outer box links each having top, bottom, side and end walls, yoke links substantially rectangular in shape and one being partly housed in each box link and embracing the end wall of the box link partly housing it and the end wall of an adjacent box link, and a spring acting between said yoke link and the box link in which it is housed whereby the bracelet may be extended in the direction of its length by

yieldingly sliding the yoke link out of the box link, one of the walls of the outer box link being resilient to permit flexing for detaching the yoke link from the end wall of the said adjacent box link.

2. An expandible bracelet comprising a series of box links, each having top, bottom and side walls and a resilient end wall, a frame link partially housed and slidably mounted in each of said box links and having one end connected to the resilient wall of the next adjacent box link which may be detached therefrom by flexing the resilient end wall, and a spring in each box link pressing its frame link to contracted position therein.

3. An expandible bracelet comprising a series of outer box links, each having top, bottom, side and end walls, an inner yoke link slidable in each box link and having an end portion located outside of the box link and engaging the end wall of the next box link, and means to permit a separation of the engaged end wall and its adjacent wall for detachment of the yoke link therefrom.

4. An expandible bracelet comprising a series of outer box links each having top, bottom, side and end walls, an inner yoke link slidable in each box link and having an end portion located outside of the box link and engaging the end wall of the next box link, said engaged end wall being resilient and having a portion separable from the other wall to permit detachment of the yoke link therefrom.

5. An expandible bracelet comprising a series of box links, each having top, bottom, side and end walls, one of the end walls being resilient and having a lip portion overlapping its bottom wall, a frame link slidably in each box link and having one end detachably connected to the resilient wall of the next adjacent box link, and a spring in each box link acting between its opposite end wall and the housed end of its frame link pressing these links toward contracted position.

In testimony whereof I affix my signature.

WILLIAM LICHTENFELS.
